UNITED STATES PATENT OFFICE.

PETER LESCH, OF NEW YORK, N. Y.

NON-REFILLING STOPPER FOR VESSELS.

SPECIFICATION forming part of Letters Patent No. 593,179, dated November 2, 1897.

Application filed January 2, 1897. Serial No. 617,774. (No model.)

To all whom it may concern:

Be it known that I, PETER LESCH, of New York city, in the county and State of New York, have invented a new and Improved 5 Stopper to Prevent Refilling of Vessels, of which the following is a full, clear, and exact description.

My invention relates to a new form of stopper which may be employed with bottles and 10 other vessels having a neck-like opening of the ordinary construction and while permitting the free egress of the contents will automatically close the opening to prevent the insertion of any additional liquid.

15 The invention consists in the novel construction and combination of the several parts, as will be hereinafter fully set forth, and pointed out in the claims.

Reference is to be had to the accompanying 20 drawings, forming a part of this specification, in which similar characters of reference indicate corresponding parts in all the views.

Figure 1 is a vertical elevation of the stopper within the bottle, the upper end of the 25 bottle being shown in section. Fig. 2 is a vertical section through the bottle and stopper. Fig. 3 is a similar view with the neck of the bottle down, showing the position of the parts when pouring out the contents of 30 the bottle; and Fig. 4 is a horizontal section on the line 4 4 of Fig. 1.

My device may be applied to bottles, jugs, or any other vessel having a neck-like opening. I have herein shown it as applied only 35 to bottles. It will, however, readily be seen that it may be as well applied to many other vessels. In using my device in connection with such vessels it is not necessary to make any change in the vessels themselves.

40 The stopper is complete in itself and independent in its operation from the structure of the containing vessels, except that the orifice in the vessel must be round and of the proper size and depth to receive the stopper.

45 The stopper is in the general form of a circular cone, having an opening in the point of the cone and a valve inside the same, which is controlled by a spring and float. The outer member B of this stopper is made

to fit closely in the orifice of the neck A of 50 the bottle or other vessel A' to which it is applied. This stopper is made, preferably, of thin metal and shaped exteriorly as a cone having a curved outline. At its upper end or point it is provided with a small orifice b. 55 Within this stopper and below this orifice are two baffle-plates B', projecting from opposite sides of the cone and overlapping each other, so as to permit the passage of the liquid but prevent the insertion of a wire within the 60 hole b to tamper with the valve. The inner or larger end of the cone B is screw-threaded on its inner surface and receives the valve-seat and spring-casing C, which screws therein.

The upper end of the casing C forms a seat 65 for the valve D, which has a stem d extending inwardly and connected to a yoke E. The lower end C² of the casing C is provided with opposite longitudinal slots C', which receive the outer ends of the yoke E and guide the 70 same. Within said casing and resting at one end upon the ledge f and at the other end upon the yoke E is a spirally-coiled spring F, which is made of sufficient strength to hold the valve D upon its seat against the 75 pressure of the liquid in the vessel.

Two arms H upon opposite sides of the stopper form a support for the pin g, upon which is pivoted the lever G, which upon its outer end has a float I pivoted thereto. This float 80 is made as light as possible, so that it will have very little weight when supported free of the liquid, but will have as great a buoyant effect as possible when immersed in the liquid. The lever G is so shaped that the 85 part on the opposite side of the pivot from the attachment of the float I will engage the yoke E when the float is moved toward the interior of the bottle. In the drawings this lever is shown as of a peculiar curved form. 90 It may, however, be made straight or approximately straight. That portion of the lever opposite the attachment of the float being so arranged as to engage the yoke E will depress the same and compress the spring F 95 when the float is immersed in the liquid by inverting the position of the vessel, as shown in Fig. 3. In such a case the buoyant power

of the float I being very much greater than its weight will have a lifting effect upon the lever sufficient to depress the opposite end and thus compress the spring and open the 5 valve D. The liquid will then be free to pass out through the opening b at the top of the portion B of the stopper.

The valve D being normally held down upon its seat by the spring F any liquid 10 poured into the opening of the neck will not have access to the interior of the bottle. The strength of the spring F and the weight of the float I will be so adjusted that the spring will be able to overcome the lifting 15 effect due to the weight of the float and will not permit the float to raise the valve. As this lifting effect is, however, greater when the float is immersed in the liquid, the valve will be pressed from its seat when the vessel 20 is inverted.

In utilizing the buoyant effect of the float for opening the valve it makes it impossible to have the valve opening with the vessel in any position except when there is sufficient 25 liquid in the vessel to lift the float.

Having thus described my invention, I claim as new and desire to secure by Letters Patent—

1. A closure for vessels, comprising a spring- 30 closed valve provided with a valve-stem extending from its inner side, a yoke on the stem and having guided movement, a pivoted lever adapted to engage said yoke to force the valve from its seat, and a float attached 35 to said lever, substantially as described.

2. A closure for vessels, comprising a spring- closed valve provided with a valve-stem, baffle-plates outside said valve, a yoke on the end of the stem, guides for said yoke, a pivoted lever adapted to engage said yoke, and a float connected with said lever and adapted by its buoyancy when in a liquid to move the said lever to engage the yoke and open the valve when the vessel is inverted, substantially 45 as described.

3. A closure for vessels, comprising a hollow plug having an opening at its outer end, a valve-seat within the said plug, a valve adapted to rest upon the said seat, a yoke 50 having guided movement and connected with the said valve, and a float adapted by its buoyancy to move the yoke to open the valve, substantially as described.

4. A closure for vessels, comprising a hollow plug consisting of an outer cone-shaped member having its larger end adapted to fit closely in the neck of a vessel, the outer end or point of the cone being provided with an opening, and an inner member secured to the 55 cone-shaped member and forming a valve-seat, a valve resting on said seat, a stem extending from said valve, and a guide-yoke attached to the said stem and having guided movement in the said inner member, and a float adapted by its buoyancy to move the 60

said yoke to open the valve, substantially as described.

5. A closure for vessels, comprising a hollow plug consisting of an outer cone-shaped member having its inner or larger end adapted to fit closely in the neck of a vessel, the outer end or point of the cone having an opening formed therein, and baffle-plates located within the cone and projecting from opposite sides thereof, and an inner member forming a valve-seat and a casing, a valve resting on said seat and provided with an inwardly-extending stem, a spring located within the said casing and serving to hold the said valve on its seat, a yoke on the end of the said stem, 70 guide-slots for the end of said yoke formed in the said casing, a pivoted lever adapted when moved to engage the yoke to compress the spring and open the valve, and a float attached to the said lever and adapted by its 75 buoyancy to move the said lever when the vessel's mouth is turned down, substantially as described.

6. A closure for vessels, comprising a hollow plug having an opening at its outer end, 80 a valve-seat within the said plug, a valve adapted to be seated on said seat and opening outward therefrom, a stem extending from the inner side of said valve, a yoke on the end of the said stem and having guided movement, a spring surrounding the said stem and pressing on the said yoke to hold the valve to its seat, and a float adapted by its 85 buoyancy to move the yoke to compress the said spring and open the valve, substantially as 90 described.

7. A closure for vessels, comprising a hollow plug adapted to fit the orifice of the vessel and having an opening in its outer end, a valve-seat within the said plug, a valve resting upon the said seat and opening outwardly 95 therefrom, a yoke having guided movement and connected with the said valve, a pivoted lever adapted to engage the said yoke to move the valve from its seat, and a float attached 100 to the said lever and adapted by its buoyancy when in a liquid to move said lever to open the valve when the vessel's mouth is turned down, substantially as described.

8. A closure for vessels, comprising a spring- held valve in the orifice of the vessel and opening outward, baffle-plates outside said valve, a stem upon the inner side of said valve, a yoke on the stem, guides for said yoke, a pivoted lever adapted to engage said yoke to 115 force the valve from its seat, and a float attached to said lever and adapted by its buoyancy in a liquid to open said valve when the vessel's mouth is turned down, substantially as described.

9. A closure for vessels, consisting of a hollow stopper adapted to fit the orifice of the vessel, said stopper having a hole in its outer end, and baffle-plates within the stopper overlapping each other and adapted to prevent 120

access to the valve by any tool, a valve ring or seat fitting within said hollow stopper, a valve opening outward from said ring or toward the opening in the stopper, a stem and 5 guide-yoke attached to the valve and lying inwardly therefrom, a guide for said yoke, and a pivoted lever having a float on one end and engaging the yoke by the other end, and

adapted by its buoyancy when in a liquid to open said valve when the vessel's mouth is 10 turned down, substantially as specified.
